(57) **CLAIM**

The ornamental design for a decanter, as shown and described.

DESCRIPTION

FIG. 1 is a perspective view of a decanter showing a first embodiment of my new design:

FIG. 2 is a top plan view thereof;

FIG. 3 is a front elevational view thereof, the rear view being a mirror image view thereof; and,

FIG. 4 is a bottom plan view thereof.

1 Claim, 4 Drawing Sheets

FIG. 1

FIG. 2

FIG. 3

FIG. 4
